DOOR LOCK

Charles C. Moler, Hartford City, Ind., assignor to Overhead Door Corporation, Hartford City, Ind., a corporation of Indiana

Filed Mar. 2, 1959, Ser. No. 796,349
12 Claims. (Cl. 70—146)

This invention relates to a lock assembly for upwardly acting doors, particularly desirable for use in connection with doors which are slidably associated with tracks.

The main objects of this invention are:

First, to provide a door and lock assembly in which the latch automatically engages when the door is moved to closed position and is provided with means for locking from the inside of the door against manipulation from the outside of the door, and one which is provided with a key-controlled lock actuating means operable from the outer side of the door.

Second, to provide a lock structure having these advantages which may be assembled with a door without substantial modifications in the structure thereof.

Third, to provide a lock structure with latch release means operable from the outer side of the door provided with a detent for holding the latch in disengaged position with tripping means therefor acting when the door is moved from closed position so that the latch will be operative when the door is returned to closed position.

Objects relating to details and economies of the invention will appear from the description to follow. The invention is defined in the claims.

A structure which embodies the features of the invention is clearly illustrated in the accompanying drawing, in which:

FIG. 1 is a fragmentary front elevation view of a door and door frame or wall illustrating an application of the invention.

FIG. 2 is an enlarged fragmentary view on a line corresponding to line 2—2 of FIG. 1.

FIG. 3 is an enlarged fragmentary view mainly in vertical section on a line corresponding to line 3—3 of FIG. 1.

FIG. 4 is a fragmentary view partially in section on a line corresponding to line 4—4 of FIG. 2 with the manually manipulatable latch lock member shown in open position by full lines and in locking position by dotted lines.

FIG. 5 is an inside perspective view of the base plate or support member with the housing removed.

FIG. 6 is a fragmentary view partially in horizontal section of an adaptation of the invention to a door having metal panels and also illustrating the latch in engaged position by full lines and in released position by dotted lines, the housing member being partially broken away.

In the accompanying drawing 1 represents a door frame provided with a jamb 2. The door 3 is of the upwardly acting sectional type comprising a plurality of hinged sections. The hinges are not illustrated as they form no part of this invention. The door sections are provided with track engaging rollers 4, tracks 5 of the channel type being provided. These tracks are mounted on brackets or supports 6.

The lock comprises a base plate or support member 7, preferably a sheet metal stamping consisting of a web portion 8 provided with holes 9 adapted to receive attaching screws. This base plate is mounted on one of the door sections adjacent one vertical edge thereof and is provided with an outer inwardly or rearwardly projecting arm 10 at one end thereof and having a slot 11 therein. The base plate is provided with an inner flange 12 having a horizontal slot 13 therein. The base plate or support member 7 has a pivot ear 14 struck from the web thereof

2

and to which the downwardly projecting pivot 15 is secured to pivotally support the latch 16 which is provided with a pivot engaging ear or lug 17. The coiled spring 18 is arranged on the pivot with one arm 19 thereof engaging the latch supporting ear 14 and the other arm 19 engaging the latch.

The latch is provided with a keeper engaging member 20 projecting through the slot 11 in the arm 10 of the base plate 7 and with a finger piece 21 at its opposite end 10 projecting through the slot 13 in the flange 12 thereof. The track is provided with a keeper 22 with which the latch engages when the door is in its fully closed position. The latch may be disengaged by pressure on the fingerpiece 21 or by means of the spring biased lockable push button 23 which is arranged in a cylinder 24, desirably fixedly secured to the base plate as indicated at 25, FIG. 3. The door has a bore 26 therein to receive this cylinder. The details of this lockable push button are not illustrated as they form no part of the present invention. The push button is outwardly biased by the spring 27.

A key is shown at 28 and may be manipulated to engage the push button bolt 29 with either the keeper opening 30 or the keeper opening 31. The keeper opening 30 is positioned to receive the bolt of the push button when it is in projected position as shown in FIG. 3, the opening 31 being positioned to receive the push button bolt 29 when it is in actuated position. The stem of the push button contacts with the lower end of the latch release lever 32 which is pivotally mounted at 33 on the inner side of the base plate flange 12, the upper end of the lever 32 being positioned at the inner side of the tripping end of the latch 16, see FIGS. 3, 4 and 5.

With this arrangement the latch can be operated from the inner side of the door by means of the fingerpiece 21. When the push button is locked in its inner position there is sufficient clearance to permit the releasing manipulation of the latch from the inner side of the door.

To prevent release of the latch from the outer side of the door by manipulation of the push button when it is unlocked I provide a latch locking member 34 which is pivoted on the stud 35 projecting from the base plate and is provided with an inwardly projecting fingerpiece 36. At its inner end the latch lock member 34 is provided with a stud 37 which engages behind the latch as illustrated in FIGS. 4 and 5, preventing any manipulation of the latch, either from the inside or outside of the door, until the latch locking member 34 is moved to latch disengaging position *a* shown by full lines in FIG. 4.

The lock is also preferably provided with a springable detent 38 mounted on the base plate below the lever 32 and in engagement therewith as shown in FIG. 3 so that when the lever 32 is actuated by the push button to release the latch, the lever is held in latch releasing position. This is of advantage in the event the operator releases the latch through the push button and does not hold the push button in latch releasing position until the latch by opening movement of the door is moved out of keeper engaging position. To insure that the latch shall be in keeper engaging position on the return of the door to closed position the trip member 39 is provided, positioned above the keeper to engage the latch as shown in FIG. 3 and thereby disengage the lever 32 from the detent 38. The latch is provided with a housing 40 which encloses all the parts with the exception of the keeper engaging portion of the latch, the fingerpiece thereof and the fingerpiece of the latch locking lever or member 34.

The escutcheon plate 41 is provided with a handhold 42 at its lower edge positioned so that the push button 70 may be operated simultaneously with the grasping of the handhold. The escutcheon plate is provided with a guard

43 of arcuate form disposed above the push button to protect the projecting end thereof.

FIG. 6 illustrates an adaptation of the invention to a door having metal panels 44. The structure is the same as described with the exception that the base plate 45 is provided with a rib or embossment 46 to compensate for the rib 47 on the door. Only one of the fasteners 48 is illustrated.

With this arrangement of parts the door may be securely locked in closed position and may be locked from either the inner side or the outer side, but when locked from the inner side it is necessary to unlock it from the inner side. If locked from the outer side it may be unlocked from the outer side.

While I have illustrated the invention as embodied in an upwardly acting door for which it is particularly desirable, it is desirable for use in other closures of the sliding type.

Having thus described the invention, what is claimed as new and is desired to be secured by Letters Patent is:

1. In combination with an upwardly acting door assembly comprising a door and tracks with which the door is slidably associated, a lock comprising a base member mounted on the inner side of the door adjacent a vertical edge thereof and to a track and having spaced inwardly projecting outer and inner slotted arms and an inwardly projecting pivot ear intermediate said arms, a latch provided with a pivot mounted on said ear and having an angled keeper engaging element disposed through the slot of the outer arm and an inwardly projecting inwardly offset fingerpiece disposed through the slot of the inner arm, a coiled spring disposed on the latch pivot with one end thereof engaged with said ear and the other with said latch and acting to yieldingly urge the latch to keeper engaging position, a keeper projecting inwardly from said track positioned to be engaged by said latch when the door is in closed position, a latch release lever pivotally mounted on the inner side of said inner arm of said base plate with its upper end disposed on the outer side of said latch, a spring biased lockable push button disposed through the door in operative relation to said latch release lever and provided with key actuated means for lockingly retaining it in actuated latch disengaging position or for locking it in projected position, a detent disposed to engage said latch actuating lever when actuated by said push button to keeper disengaging position, an outwardly facing trip member disposed on said track in upwardly spaced relation to said keeper and acting to disengage the latch from said detent when the door is raised from its closed keeper engaging position, and an inner manually operable latch lock member pivotally mounted on said base plate for manual adjustment to and from latch locking position.

2. In combination with an upwardly acting door assembly comprising a door and tracks with which the door is slidably associated, a lock comprising a base member mounted on the inner side of the door adjacent a vertical edge thereof and to a track and having spaced inwardly projecting outer and inner slotted arms and an inwardly projecting pivot ear intermediate said arms, a latch provided with a pivot mounted on said ear and having an angled keeper engaging element disposed through the slot of the outer arm and an inwardly projecting inwardly offset fingerpiece disposed through the slot of the inner arm, a coiled spring disposed on the latch pivot with one end thereof engaged with said ear and the other with said latch and acting to yieldingly urge the latch to keeper engaging position, a keeper projecting inwardly from said track positioned to be engaged by said latch when the door is in closed position, a latch release lever pivotally mounted on the inner side of said inner arm of said base plate with its upper end disposed on the outer side of said latch, a spring biased lockable push button disposed through the door in operative relation to said lever and provided with key actuated means

5 for lockingly retaining it in actuated latch disengaging position or for locking it in projected position, and an inner manually operable latch lock member pivotally mounted on said base plate for manual adjustment to and from latch locking position.

3. The combination with an upwardly acting door assembly comprising a door and tracks with which the door is slidably associated, of a lock comprising a base member mounted on the inner side of the door adjacent a vertical edge thereof and to a track, a spring biased latch pivotally mounted on said base member and having a fingerpiece at its inner end, a keeper projecting inwardly from said track positioned to be engaged by said latch when the door is in closed position, a latch release lever pivotally mounted on said base member with one end disposed on the outer side of said latch, a spring biased lockable member disposed through the door in operative relation to said lever and provided with key actuated means for lockingly retaining it in actuated latch disengaging position or for locking it in retracted position, a springable detent on said base member disposed to engage said latch actuating lever when actuated by said push button to latch disengaging position, a trip member disposed in upwardly spaced relation to said keeper and acting to disengage the latch actuating lever from said detent when the door is raised from its locking position, and an inner manually operable latch lock member pivotally mounted on said base plate for manual adjustment to and from latch locking position.

4. The combination with an upwardly acting door assembly comprising a door and tracks with which the door is slidably associated, of a lock comprising a base member mounted on the inner side of the door adjacent a vertical edge thereof and to a track, a spring biased latch pivotally mounted on said base member and having a fingerpiece at its inner end, a keeper projecting inwardly from said track positioned to be engaged by said latch when the door is in closed position, a latch release lever pivotally mounted on said base member with one end disposed on the outer side of said latch, a spring biased lockable member disposed through the door in operative relation to said latch release lever and provided with key actuated means for lockingly retaining it in actuated latch disengaging position or for locking it in projected position, and an inner manually operable latch lock member pivotally mounted on said base plate for manual adjustment to and from latch locking position.

5. The combination with an upwardly acting door assembly comprising a door and tracks with which the door is slidably associated, of a lock comprising a base member mounted on the inner side of the door adjacent a vertical edge thereof and to a track, a spring biased latch pivotally mounted on said base member and having a fingerpiece at its inner end, a keeper projecting inwardly from said track positioned to be engaged by said latch when the door is in closed position, a latch release lever pivotally mounted on said base member with one end disposed on the outer side of said latch, a spring biased lockable member disposed through the door in operative relation to said latch release lever and provided with key actuated means for lockingly retaining it in actuated latch disengaging position or for locking it in projected position, an inner manually operable latch lock member pivotally mounted on said base plate for manual adjustment to and from latch locking position, and a housing member mounted on said base plate to enclose the parts mounted thereon with the latch keeper engaging element, the latch fingerpiece and the latch locking member projecting therefrom.

6. The combination with an upwardly acting door assembly comprising a door and tracks with which the door is slidably associated, of a lock comprising a base member mounted on the inner side of the door adjacent a vertical edge thereof and to a track, a spring biased latch pivotally

totally mounted on said base member and manually releasable from the inner side of the door, a keeper on said track positioned to be engaged by said latch when the door is in closed position, a lockable latch release member operable from the outer side of the door and provided with key actuated means for lockingly retaining it in actuated latch disengaging position or for locking it in projected position, a detent operatively associated with said latch release member for holding it in actuated latch disengaging position, a trip member disposed in upwardly spaced relation to said keeper and acting to disengage the latch release member from said detent when the door is raised from its locking position, and a manually operable latch lock member mounted on said base member for manual adjustment to and from latch locking position.

7. The combination with an upwardly acting door assembly comprising a door and tracks with which the door is slidably associated, of a lock comprising a base member mounted on the inner side of the door adjacent a vertical edge thereof and to a track, a spring biased latch pivotally mounted on said base member and manually releasable from the inner side of the door, a keeper on said track positioned to be engaged by said latch when the door is in closed position, a lockable latch release member operable from the outer side of the door and provided with key actuated means for lockingly retaining it in actuated latch disengaging position or for locking it in projected position, and a manually operable latch lock member mounted on said base member for manual adjustment to and from latch locking position.

8. A lock assembly for slidably mounted closures comprising a base member having spaced inwardly projecting outer and inner slotted arms on the opposed edges thereof and an inwardly projecting pivot ear intermediate said arms, a latch provided with a pivot mounted on said ear and having an angled keeper engaging element disposed through the slot of the outer arm and an inwardly projecting inwardly offset finger-piece disposed through the slot of the inner arm, a coiled spring disposed on the latch pivot with one end thereof engaged with said ear and the other end with said latch and acting to yieldingly urge the latch to keeper engaging position, a latch release lever pivotally mounted on the inner side of said inner arm of said base member with one end disposed on the outer side of said latch, a lockable push button assembly operatively associated with said latch release lever and provided with key actuated means for lockingly retaining it in actuated latch disengaging position or for locking it in projected position, a keeper, a springable detent disposed on said base member to engage said latch release lever when actuated by said push button to latch actuated disengaging position, a trip member disposed in spaced relation to said keeper and acting to disengage the latch release lever from said detent when the closure member on which the lock is mounted is moved from closed position, and an inner manually operable latch lock member mounted on said base member for manual adjustment to and from latch locking position.

9. A lock assembly for slidably mounted closures comprising a base member having inwardly projecting outer and inner slotted arms on the opposed edges thereof and an inwardly projecting pivot ear intermediate said arms, a latch provided with a pivot mounted on said ear and having an angled keeper engaging element disposed through the slot of the outer arm and an inwardly projecting inwardly offset finger-piece disposed through the slot of the inner arm, a coiled spring disposed on the latch pivot with one end thereof engaged with said ear and the other end with said latch and acting to yieldingly urge the latch to keeper engaging position, a latch release lever pivotally mounted on the inner side of said inner arm of said base member with one end disposed on the outer side of said latch, a lockable push button assembly operatively associated with said lever and

provided with key actuated means for lockingly retaining it in actuated latch disengaging position or for locking it in projected position, and an inner manually operable latch member mounted on said base member for manual adjustment to and from latch locking position.

10. A lock assembly for slidably mounted closures comprising a base member, a spring biased latch having a keeper engaging element at one end and a fingerpiece at the other, a latch release lever pivotally mounted on said base member for actuating said latch to keeper disengaging position, a manually operable spring biased latch release member provided with key actuated means for lockingly retaining it in actuated latch disengaging position or for locking it in projected position, a keeper, a detent disposed to automatically engage said latch release lever when actuated by said latch release member to keeper disengaging position, a trip member disposed in spaced relation to said keeper and acting to disengage the latch release lever from said detent when the closure member on which the lock is mounted is moved from closed position, and an inner manually operable latch lock member mounted on said base member for manual adjustment to and from latch locking position.

11. A lock assembly for a slidably mounted closure comprising a base member adapted to be mounted on the inner side of the closure, a spring biased keeper engaging latch pivotally mounted on said base member for swinging laterally relative to the path of travel of the closure on which the base member is mounted, said latch having a keeper engaging portion at its outer end projecting laterally from the base member for engagement with a keeper and a finger piece portion at its inner end projecting from said base member, a release lever disposed transversely of said latch pivotally mounted on said base member with one end in overlapping relation to said latch laterally of its pivot, a manually operable spring biased combined latch release and lock member mounted on said base member to coact with the other end of said release lever and to project through and manipulatable from the outer side of the closure on which the base member is mounted, said latch release and lock member including key actuating means for selectively locking it in its projected position in which position said release lever may move on its pivot independently thereof and also for lockingly retaining it in its actuated position, and an inner manually operable lock member adjustably mounted on said base member for manual adjustment to and from engagement with said latch and acting when engaged therewith to hold said latch in keeper engaging position, said inner lock member being accessible only from the inner side of the closure on which said base member is mounted.

12. A lock assembly for a slidably mounted closure comprising a base member adapted to be mounted on the inner side of the closure, a spring biased keeper engaging latch pivotally mounted on said base member for swinging laterally relative to the path of travel of the closure on which the base member is mounted, said latch having a keeper engaging portion at its outer end projecting laterally from the base member for engagement with a keeper and a finger piece portion at its inner end projecting from said base member, a release lever disposed transversely of said latch pivotally mounted on said base member with one end in overlapping relation to said latch laterally of its pivot, a manually operable spring biased combined latch release and lock member mounted on said base member to coact with the other end of said release lever and to project through and manipulatable from the outer side of the closure on which the base member is mounted, said latch release and lock member including key actuating means for selectively locking it in its projected position in which position said release lever may move on its pivot independently thereof and also for lockingly retaining it in its actuated position.
